CLAIM

The ornamental design for a cutting insert for milling cutters, as shown and described.

DESCRIPTION

FIG. 1 is a top perspective view of a cutting insert for milling cutters showing our new design;

FIG. 2 is a top view thereof;

FIG. 3 is a side view thereof;

FIG. 4 is a bottom view thereof;

FIG. 5 is an enlarged perspective view of a corner of the insert; and,

FIG. 6 is a cross-sectional view of the insert, taken at section 6—6 of FIG. 2.
